UNITED STATES PATENT OFFICE.

WILLIAM D. OSTERHOUDT, OF POUGHKEEPSIE, NEW YORK.

ADJUSTABLE CAR-STEP.

1,083,127.

Specification of Letters Patent.

Patented Dec. 30, 1913.

Application filed May 27, 1913. Serial No. 770,186.

To all whom it may concern:

Be it known that I, WILLIAM D. OSTERHOUDT, a citizen of the United States, residing at Poughkeepsie, in the county of Dutchess and State of New York, have invented new and useful Improvements in Adjustable Car-Steps, of which the following is a specification.

Railway coaches for the most part have fixed steps whereby ingress and egress is had. Such steps terminate some distance from the road bed in order to prevent their coming in contact with objects and becoming broken or disabled. This necessitates the use of a box or like device to enable the passenger to reach the first step when entering the car or to leave the last step when leaving the car.

The present invention provides an adjustable step which when not required for immediate use may be elevated so as to be out of the way and which when required for use may be lowered thereby providing for the convenience of the traveling public when entering or leaving a passenger coach.

The invention consists of bars slidably mounted beneath the ordinary car steps so as to be out of the way, said bars having a limited sliding movement and being connected by means of braces. Brackets are pivotally and adjustably connected with the lower ends of the sliding bars and a step is attached to such brackets, the parts being arranged so that when the movable step is elevated it occupies a position beneath the lowermost or first step of the ordinary car steps and which movable step when lowered is firmly supported in convenient position to admit of passengers entering or leaving the car with ease and convenience.

The invention consists of the novel features, details of construction and combination of parts, which hereinafter will be more particularly set forth, illustrated in the accompanying drawings, and pointed out in the appended claims.

Referring to the drawings, forming a part of the specification, Figure 1 is a detail view in perspective of a pair of car steps provided with an adjustable car step embodying the invention. Fig. 2 is a vertical longitudinal section of the steps, the dotted lines showing the movable step elevated and the full lines illustrating the position of the movable step lowered. Fig. 3 is a view

of the steps as seen from the under side. Fig. 4 is a detail view of one of the brackets for the movable step. Fig. 5 is a detail view showing more clearly the adjustable stop fitted to each of the slideable bars to limit its downward movement.

Corresponding and like parts are referred to in the following description, and indicated in all the views of the drawings, by the same reference characters.

The numeral 1 designates the fixed steps such as generally provided at the ends of the platform of passenger coaches, said steps being stationary and comprising stringers 2, treads 3 and risers 4. Hangers 5 and 6 are secured to the stringers 2 of the steps and slidably support bars 7 which have their lower ends widened as indicated at 8. The bars 7 slide through openings formed in the lower ends of the hangers 5 and 6 and have a limited sliding movement which is determined by the movable step 8 and adjustable stops 9 the latter being secured to the bars 7 near their upper ends and arranged to engage the hangers 5 so as to limit the downward movement of the bars when the step 8 is at the limit of its downward movement. Braces 10 connect the bars 7 such braces crossing intermediate of their ends and having their terminal portions bent and apertured to receive fastenings by means of which said braces are connected to the bars 7. A cable 11 or like flexible connection is attached to the braces 10 preferably at their point of crossing, said cable passing over a guide pulley 12 and extending within convenient reach to be operated to effect a raising or lowering of the movable step 8. A roller 13 is located at the lower end of each of the hangers 6 and reduces the friction between the bar 7 and hanger so that the movable step may be easily raised or lowered when operating the cable 11 or like part.

A bracket 14 is provided for each end of the movable step 8 and is secured thereto, said bracket having its rear portion widened as indicated at 15 and formed with an arcuate slot 16 which is concentric with the pivot fastening 17 between such bracket and the lower end of the bar 7. A fastening 18 supported in the lower end of the bar 7 passes through the slot 16 and serves to secure the bracket 14 in the required position thereby admitting of the bracket and a movable step 8 being adjusted so as to occupy a relatively

horizontal position. The movable step 8 is secured to the brackets 14 in any convenient and substantial way.

When installing the invention the hangers 5 and 6 are located near the upper and lower ends of the stringers 2 of the ordinary car steps and the bars 7 are so arranged that when they are moved upward the step 8 comes beneath the lower or first step of the stationary car steps. The stops 9 are so adjusted that when the step 8 is lowered to the predetermined position they engage the hangers 5. It is to be understood that it is preferred to arrange the parts so that when the movable step 8 is lowered it occupies a position about midway between the platform at the station and the first step of the stationary car steps thereby adding to the convenience of the passenger when entering or leaving the car. When it is desired to elevate the movable step 8 the cable or flexible connection 11 is drawn upon thereby causing the bars 7 to slide in the hangers 5 and 6 with the result that the step 8 is brought to position beneath the lower or first step of the stationary car steps as indicated by dotted lines in Fig. 2.

From the foregoing description, taken in connection with the accompanying drawings, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claims appended hereto.

I claim:—

1. In combination with the usual stationary car steps, a bar slidably beneath such

steps, a bracket adjustably connected with the lower end of the bar and movable therewith and a step attached to said bracket and adapted to come beneath the lowermost tread of the car steps when the bar is elevated.

2. In combination with the usual stationary car steps, hangers having connection with such steps, a bar slidably mounted in the hangers, a step connected with the lower end of the bar and adapted to occupy a position beneath the lowermost tread of the steps when the bar is elevated and a stop adjustably connected with the bar to limit the downward movement of the bar and step when the latter is lowered.

3. In combination with the usual stationary steps of cars, bars slidable beneath such steps and having their lower ends widened, brackets having their inner ends widened and pivotally connected with the lower ends of the bars and formed in their widened ends with arcuate slots, means for securing the brackets to the bars in the desired adjusted position and a step connected with such brackets.

4. In combination with the usual stationary steps of cars, hangers having connection with the stringers of such steps, bars slidably mounted in the hangers, braces connecting the bars, stops adjustably connected with the bars and adapted to engage one of the hangers to limit the downward movement of the bars, a step connected with the lower ends of the bars and a flexible connection attached to the crossed braces and adapted to extend within convenient reach to admit of operation of the bars when it is required to raise or lower the movable step.

In testimony whereof I affix my signature in presence of two witnesses.

WILLIAM D. OSTERHOUDT.
